DOOR HINGE

Malcolm F. Webber, Detroit, Mich., assignor to
General Motors Corporation, Detroit, Mich.,
a corporation of Delaware

Application April 17, 1937, Serial No. 137,385

7 Claims. (Cl. 296—44)

This invention relates to an improvement in the structures of doors and the concealing of door hinges and the uniting therewith of the cowl light.

5 In present automotive practice the hinges for the doors project outwardly from the body and leave a somewhat unsightly or objectionable appearance. There is also usually formed on the automobile body a belt molding extending there-
10 around and across the door. In the present invention, advantage is taken of the usual belt molding to conceal the hinge and also to combine with the forward end of the molding at the cowl the usual cowl lights.

15 On the drawing

Figure 1 is a perspective view of a part of an automotive vehicle showing the invention applied.

Figure 2 is a section on the line 2—2 of Figure 1, the open position of the door being shown in dotted lines.

Figure 3 is a section on the line 3—3 of Figure 2.

On the drawing the numeral 2 indicates as a whole the body of an automotive vehicle. The body has the cowl 4, the windshield 6, the front door pillar 8, the rear door pillar 11 and the door 10 the latch of which is operated by the handle 12. The door is equipped with the usual shiftable window 14.

In modern automotive practice it has been customary slightly to taper the body from the bottom toward the top so that the upper hinge 16 projects outwardly a considerable distance from the door as is indicated by the position of the knuckle 18 of the hinge in Figures 2 and 3. It is the object of the invention to conceal this projecting part of the hinge and to combine therewith the usual cowl light.

40 There is accordingly formed in the door a channel 22 in alignment with the usual belt molding 20. This channel may taper from the end 24 where it aids in concealing the hinge to the other end 26 where it mates with the molding 20 of the body proper. The channel or molding 22 may be pressed directly into the exterior metal panel 28 of the door. The end 24 has an arcuate part 30 which fits into a corresponding arcuate part 32 on a channel member 34 secured onto the body 2 at the front door pillar 8 in alignment with the channel 22 on the door. The channel 34 has the lateral flanges 36 which fit under the metal of the outer skin of the body 2 and are suitably welded in place. The channels 22 and 34 therefore form a continuation of

each other and conceal the knuckle 18 of the hinge as is best shown in Figures 2 and 3. The arcuate parts 30 and 32 enable the opening of the door as is best illustrated in the full and dotted line positions shown in Figure 2.

5 The channel 34 is open at its two ends and in the outermost end there is fitted and secured the glass 38 of a cowl lamp. The glass 38 preferably has a part or a flange, indicated in dotted outline by the numeral 40, which extends into the channel 34. The other end of the glass 38 runs into a tip 42 to give a neat appearance. In other words, the glass 38 tapers gradually from the channel 34 to the tip 42 and its back lies closely in contact with the body 2. A bead 43 may be used around the edge of the glass 38.

The hinge 16 itself comprises the leaves 44 and 46 which are secured respectively to the pillar 8 and the door 11. They are held together by means of the pintle or pin 48 passing through 20 suitable aligned openings in the knuckle 18. Suitable antiseak material 50 is provided between the pintle 48 and the knuckle member of the leaf 46.

I claim:

1. In combination with a hinge of the door of an automotive vehicle, said hinge projecting away from the plane of the outer surface of the door, a channel formed in the door in alignment with the hinge, a channel on the door pillar adjacent the hinge and in alignment with the door channel, said channels being closely juxtaposed and concealing the hinge. 30

2. In combination with a hinge of the door of an automotive vehicle, said hinge projecting 35 away from the plane of the outer surface of the door, a channel formed in the door in alignment with the hinge, a channel on the door pillar adjacent the hinge and in alignment with the door channel, said channels being closely 40 juxtaposed and concealing the hinge, and a cowl light glass at the end of the second named channel and forming a continuation thereof.

3. In combination with a hinge of the door of an automotive vehicle, said hinge projecting 45 away from the plane of the outer surface of the door, a channel formed in the door in alignment with the hinge, a separate channel attached to the door pillar adjacent the hinge and in alignment with the door channel, said channels being 50 closely juxtaposed and concealing the hinge.

4. In combination with a hinge of the door of an automotive vehicle, said hinge projecting away from the plane of the outer surface of the door, a channel formed in the door in alignment

with the hinge, and a channel on the door pillar adjacent the hinge and in alignment with the door channel, said channels being closely juxtaposed and concealing the hinge, the juxtaposed ends of the channels being of arcuate shape to enable the door to open and close.

5. In combination with a hinge of the door of an automotive vehicle, said hinge projecting away from the plane of the outer surface of the door, a channel formed in the door in alignment with the hinge, and a channel on the door pillar adjacent the hinge and in alignment with the door channel, said channels being closely juxtaposed and concealing the hinge, the pivot of the hinge being inside the door channel.

10. In combination with a hinge of the door of an automotive vehicle, said hinge projecting away from the plane of the outer surface of the

door, a channel formed in the door in alignment with the hinge, a channel on the door pillar adjacent the hinge and in alignment with the door channel, said channels being closely juxtaposed and concealing the hinge, and a cowl light glass 5 tapering from the channel to the body and forming a continuation of the pillar channel.

15. In an improvement for a vehicle body having a cowl, a front door and a rear body part, a strengthening rib on the cowl, a strengthening 10 rib on the door, a strengthening rib on the rear body part, said ribs being in alignment and forming continuations of each other, a hinge for the door, said hinge being concealed by the ribs on the cowl and door, and a cowl light transparency 15 on the cowl and forming a continuation of the cowl strengthening rib.

MALCOLM F. WEBBER.
